UNITED STATES PATENT OFFICE.

SAMUEL RUBEN, OF NEW YORK, N. Y.

ELECTRON-DISCHARGE TUBE.

Application filed June 28, 1923. Serial No. 648,398.

To all whom it may concern:

Be it known that I, SAMUEL RUBEN, a citizen of the United States, and resident of New York city, in the county of New York and State of New York, have invented certain new and useful Electron-Discharge Tubes, of which the following is a specification.

This invention relates to an electron discharge tube; and more particularly, it relates to an electron discharge device for the detection and amplification of radio frequency oscillations. Its object is to provide an efficient low cost means for detecting and amplifying received radio frequency oscillations.

In the prior art there are two types of electron discharge tubes, the two element tube employing a hot cathode and a cold anode and functioning by virtue of the rectification effected by means of the hot cathode; and the three element tube, employing the hot cathode and an anode, and a third element for electrostatically modulating the electron discharge from the cathode to the anode. The tube of my invention is of the former type, but possesses the characteristics of the latter.

Broadly, my invention consists of a vacuum tube apparatus, the electron discharge of which traverses an electrostatic field between the cathode element and the anode, and having an insulating plate element interposed across the normal direct path of that discharge to the anode, which is forced thereby to travel across the electrostatic field in a direction approaching an angle of 45 degrees to the direction of the field, by the variations in which, in response to radio frequency oscillations impressed upon the anode-cathode circuit, the electron discharge is modulated.

As arranged, the cathode and anode, comprising conductive surfaces in combination, act as condenser electrodes, between which, when radio frequency oscillations are impressed, a capacity current flows transverse of the electron current. Thus, this two element tube rectifies impressed oscillations and electrostatically modulates the electron discharge between the cathode and anode, and adds an amplification characteristic to this type of tube, rendering the tube many times as sensitive as those of the prior art.

The principle of the invention can best be explained in connection with a certain

illustrative embodiment of the invention shown in the accompanying drawings, in which—

Fig. 1 is a vertical sectional view of the tube;

Fig. 2 is a sectional view of the contained elements, and indicates the directions of the electron stream and the capacity current;

Fig. 3 is a diagram of a radio receiving circuit in which the tube is connected.

Referring more particularly to Fig. 1, 1 is a receptacle composed of glass or other suitable material, containing a filament cathode 6, and an anode 2, the former supported by 70 and in conductive relation with plates 3 and 4, of large area for large electrostatic capacity. Opposite the filament cathode 6, and attached to anode 2, is a mica plate 5, to deflect the electron stream from its normal direct path to the anode 2, forcing it to traverse the electrostatic field in a direction approximately 45 degrees to that of the field in the space between plates 3 and 4, and anode 2, the lead from which latter is at 9, 80 and those from the cathode at 7 and 8.

For some uses the mica surface adjacent the cathode, can with advantage be coated with a conductive material, such, for instance, as graphite.

By extending the anode element to the opposite side of the plane of the filament and its supporting plates, and interposing a non-conductive material, as in the first instance, a more efficient use of the electron discharge from the filament is effected.

In Fig. 3, L indicates the generally used tuning inductances, the secondary connected to anode element 2, and to battery B_2 , which furnishes the potential for the electron discharge between the electrodes. A telephone receiver T , translates the impressed electrical oscillations into sound waves. C_2 is a by-pass condenser for radio frequency oscillations, and B_1 is a battery 100 for heating the cathode to emission temperature, controlled by resistance R .

In operation, when the cathode is sufficiently heated by battery B_1 for electron emission, a current flows between the cathode and anode and through the circuit including telephone receiver T . Radio frequency oscillations impressed upon the anode-cathode circuit from the secondary of the tuning device L , cause the discharge 110 of a capacity current between cathode plates 3 and 4, and anode 2, which, varying in re-

sponse to the impressed oscillations, modulates the electron discharge traversing it. It has been found that, for the most efficient modulation of that discharge, the angular relation between the discharges is about 45 degrees.

Modulations of the electron discharge are translated by telephone receiver T.

If used for detection purposes only, this 10 apparatus need not be so highly evacuated as for purposes of amplification.

What I claim is—

1. An electron discharge tube comprising an evacuated vessel having therewithin an 15 electron emission element, a cooperating plate or anode element and an element composed of an insulating material, interposed therebetween, and electrically conductive plates arranged in a plane approximately 20 parallel to said anode element, said emission element being in conductive relation with said conductive plates.
2. An electron discharge tube comprising an evacuated vessel having therewithin an 25 electron emission element, a cooperating plate or anode element and an element com-

posed of insulating material, interposed therebetween in the normal path of the electron discharge between said cathode and said anode, and electrically conductive 30 plates arranged in a plane approximately parallel to said anode element, said emission element being in conductive relation with said conductive plates.

3. An electron discharge tube comprising 35 an evacuated vessel having therewithin an electron emission element, a cooperating plate or anode element, and electrically conductive plates arranged in a plane approximately 40 parallel to said anode element, said emission element being in conductive relation with said conductive plates and means for deflecting the electron discharge from its normal path to said anode element to a path transverse of the direction of a capacity current flowing between said conductive 45 plates and said anode.

Signed at New York city, in the county of New York and State of New York, this 23rd day of June, A. D. 1923.

SAMUEL RUBEN.
